Attorney

UNITED STATES PATENT OFFICE.

MAX SCHWEINSHAUT, OF ATTLEBORO, MASSACHUSETTS, ASSIGNOR TO M. S. COMPANY, OF ATTLEBORO, MASSACHUSETTS.

KEY POUCH.

1,426,782.

Specification of Letters Patent. Patented Aug. 22, 1922.

Application filed February 9, 1922. Serial No. 535,222.

To all whom it may concern:

Be it known that I, MAX SCHWEINSHAUT, a citizen of the United States, residing at Attleboro, in the county of Bristol and State 5 of Massachusetts, have invented new and useful Improvements in a Key Pouch, of which the following is a specification.

This invention relates to certain new and useful improvements in a key pouch, and 10 pertains more particularly to a pouch or case which is employed to carry keys in the pocket or otherwise.

The primary object of the invention is to provide improved means for holding the 15 keys, which means allows of the keys being easily moved beyond the end of the case, and which also allows same to be freely turned in all directions without requiring corresponding movement of the case, or in 20 other words to allow the keys to be freely turned independent of the case and of the remaining keys carried by the case.

A further object of the invention is to provide means for mounting the keys so 25 that all of same may be easily and quickly swung out beyond the end of the case and as easily returned to lie within the case.

The invention still further aims to provide a simple and novel one-piece structure 30 for hingedly supporting all of the keys and for also allowing of independent turning of each.

Still further the invention aims to provide a simple and inexpensive structure and 35 one in which the parts are not subject to easy derangement.

Further and other objects will be later set forth and manifested in the course of the following description.

40 In the drawing:

Figure 1 is a plan view with the pouch in completely open position;

Figure 2 is an enlarged section on line 2-2 of Figure 1, but with the pouch in 45 closed position;

Figure 3 is a plan view of the plate secured to the pouch, illustrating the blank from which the plate is formed, and

Figure 4 is a similar view of the hinged 50 plate.

In proceeding in accordance with the present invention a pouch or case 1 is employed having closure flaps 2 and 3 secured by a snap fastener or the like 4. A

metal plate 5 is doubled upon itself and is 55 suitably secured by fastenings 6 adjacent to one end of the case and has outwardly projecting hinge knuckles 7 formed at its line of doubling and between which is received an elongated knuckle 8, a pintle 9 60 being passed through the knuckles so as to hingedly relate the parts. The knuckle 8 is formed by bending a plate between its sides so that the plate has two leaves 10, the leaves being provided with registered openings 11 and with transverse concavities 12. The concavities extend from the openings 11 through the free edges of the leaves, and are in register so as to conjointly form sockets for the shanks of eyes 13. The 70 shanks are headed at 14 while the eyes abut the free side edges of the leaves, the heads 14 being disposed in the openings 11 and abutting the outer side walls resultant from the formation of the openings. The shanks 75 are freely turnable in the sockets, though longitudinal movement thereof is prevented by virtue of the eyes and heads abutting the adjacent parts of the leaves. Rivets or other suitable fastenings 15 are employed and 80 which are driven through the leaves so as to hold the latter in contacting relation and thus prevent movement of the leaves and consequently of the shanks of the eyes, excepting as to the aforementioned rotary 85 movement of the shanks. Double ended hooks 16 are secured at one end in the eyes, while their opposite ends receive the heads of the keys. From the foregoing it will be seen that the key supporting member can 90 be swung about the pintle 9 to lie within or without the case and that each key can be rotated without effecting rotation of the case, or independently of the latter. The key supporting member is further held 95 against other than a hinging movement by the knuckles 7, and same functions to not only support all of the keys but also each so that same may be turned independently of the others.

Having thus described my invention, what I claim as new and desire to secure by Letters Patent is:

1. In a key pouch, a case, a plate secured to the case and having spaced hinged knuckles at its ends, a plate doubled upon itself to form a knuckle received between the first named knuckles, a pintle passed

through all of the knuckles, the leaves resultant from doubling of the plate being formed with openings adjacent to the knuckle thereof and with registering 5 cavities extending from the openings through the free outer side edges of the leaves, the respective concavities conjointly forming sockets, eyes having shanks turnable in the sockets, the eyes abutting the 10 free outer side edges of the leaves and the shanks having heads disposed within the respective openings, and key holding members carried by the eyes.

2. In a key pouch, a case, a plate secured 15 thereto, a member hinged to the plate, a series of independently rotatable members carried by the hinged member, and key hold-

ing devices connected to the respective rotatable members.

3. In a key pouch, a case, a plate secured 20 thereto, a second plate doubled upon itself to form a knuckle, means to hinge the knuckle to the first plate, the doubled parts of the second plate having concavities which respectively register to form sockets, and 25 key carrying members rotatable in the sockets.

In testimony whereof I have signed my name to this specification in the presence of a subscribing witness.

MAX SCHWEINSHAUT.

Witness:

J. A. MILLER.
